UNITED STATES PATENT OFFICE

GEORGE J. CARNEY, OF LOWELL, MASSACHUSETTS.

GUN-WAD.

SPECIFICATION forming part of Letters Patent No. 236,304, dated January 4, 1881.
Application filed September 22, 1880. (No model.)

To all whom it may concern:

Be it known that I, GEORGE J. CARNEY, of Lowell, in the county of Middlesex and State of Massachusetts, have invented a new and useful Improvement in Gun-Wads, which improvement is duly set forth in the following specification, reference being had to the accompanying drawings, to wit:

It is well known that the wad which is placed immediately over the shot in fire-arms is an impediment to the flight of the shot after it leaves the gun and until it falls. By its action the central pellets of the charge, which, by reason of their more perfect form, have the greatest penetration, are retarded and their efficiency is diminished thereby. By my invention the wad immediately over the shot is caused to fly through the air edgewise and not flatwise, thus allowing the center of the charge of shot to pass by the wad with more fatal effect.

In the drawings, Figure 1 represents a flat gun-wad with a hole punched in it. The dotted line represents a portion of lead inserted there-in preparatory to compression. Fig. 2 represents a similar wad with the hole in it filled with compressed lead. Figs. 3 and 4 represent cross-sections of flat gun-wads, A indicating the forms which portions of lead compressed

may assume.

In the accompanying drawings, A represents a portion of material of greater density

than the remaining portions of the wad, by reason of which the wad will be turned upon its edge in its flight. The same result obtains if a portion of matter is removed from instead of being added to one side of a wad.

I define a method of making the gun-wads as follows: The ordinary flat-cut gun-wads, of textile material, leather, or other suitable material, are placed eccentrically in the jaws of a punch, which removes by its action a portion of the material of which the wad is composed; then a cylinder of lead or suitably-shaped portion of other suitable material of greater length than the thickness of the wad and of the same diameter as the hole left in the wad by the punch, is placed in the hole in the wad and then compressed in the direction of its length, by which the metal assumes a flattened cheese-shaped form, the portion of the metal which bulges out entering the sides of the hole in the wad, thus preventing its accidental removal. The wad may then be covered with a layer of paper or suitable material pasted on each side of the wad, and it is ready for use.

I claim as my invention—

A flat-disk gun-wad, weighted at one side by an inserted piece of denser material, or its equivalent, substantially as described.

GEORGE J. CARNEY.
